DESIGN FOR A HANDBAG OR SIMILAR ARTICLE

Dorothy Portser, New York, N. Y.

Application February 16, 1943, Serial No. 109,554

Term of patent 3½ years

To all whom it may concern:

Be it known that I, Dorothy Portser, a citizen of the United States of America, residing in New York city, county of New York, and State of New York, have invented a new, original, and ornamental Design for a Handbag or Similar Article, of which the following is a specification, reference being had to the accompanying drawing, forming part thereof.

Fig. 1 is a front perspective view of a handbag or similar article showing my new design in closed position, with the handle in position when carried by hand;

Fig. 2 is a view of the opposite side thereof with the handle strap unfastened and in partly extended position; and

Fig. 3 is a front perspective view thereof with the cover in open position and the handle extended to its shoulder carrying position.

The design for the handbag disclosed is characterized by the handle thereon of the specific configuration and arrangement shown.

I claim:

The ornamental design for a handbag or similar article substantially as shown and described.

DOROTHY PORTSER.
